United States Patent Office.

EDWIN P. RUSSELL, OF MANLIUS, NEW YORK.

Letters Patent No. 97,965, dated December 14, 1869.

IMPROVED CLOTHES-WRINGER.

The Schedule referred to in these Letters Patent and making part of the same

To all whom it may concern:

Be it known that I, EDWIN P. RUSSELL, of the town of Manlius, in the county of Onondaga, and State of New York, have invented a new and improved Clothes-Wringer; and I do hereby declare that the following is a full, clear, and exact description of the same, reference being had to the accompanying drawings, and to the letters of reference marked thereon, wherein—

Figure 1 is a perspective view of the whole machine.

Figure 2 is a like view of the attaching-arrangement.

A is the upper roller, which may be made of wood, or of wood and rubber combined, in the ordinary form, or any other material in common use.

In like manner, and of about the same size, I make an under roller, B, with a loose rubber tube, *a*, (with a bore somewhat larger than the roller,) encircling the same, and large enough, so that, when used, it will operate as an eccentric band.

By making the rubber tube *a* loose upon the roller, it presents a softer and more flexible surface, takes less material, and obviates the difficulties which arise when the drive-roller turns on the shaft, as is apt to be the case with rubber rollers.

In my machine, the rubber tube *a* is fed between the rollers, making nearly as many revolutions as the drive-roller.

A like rubber tube may also be used upon the upper roller A, dispensing with it upon the lower roller; or, if desired, both may be used.

C and C' are end supports, made of metal, in pairs, substantially in the form shown in the drawings, with a hole, *d*, for the bearing of the shaft, D, of the under roller B, and with an arm, *e*, having a hole, *f*, for the bolt, which holds the swing-lever arrangements F F', and it is made to rest upon the swing-standards S S' by means of the shoulder *g*, through which is a hole for a screw-bolt, *h*, held by the tail-nut *n*.

The standards S S' are made with a base, *m*, to rest on the top of the tub, and with a shank, *n*, for one

side of the tub, and shank *o* for the other side, on which is an arbor, *p*, for the cam or eccentric-lever *l* which forms an easy and effectual means of fastening the wringer to the tub.

By means of the screw-bolt *h* and the tail-nut *n*, the standards S S' may be readily adjusted to tubs of different diameters, and easily held in position.

The end supports C and C' are also provided with an arm, *q*, to receive the rubber spring *t*, which holds down the swing-lever arrangements F F'.

The swing-lever arrangements F and F' are pivoted to the arms, *e*, of the end supports C and C' in any ordinary manner, and consist of a main lever, M, which, by a proper hole and bearing, sustains the upper roller A; an auxiliary lever, W, pivoted to the outer end of the main lever M, with a cam-bed or beds, *z z'*, at the inner end thereof, and a proper shank at the outer end, for receiving the rubber spring *t*; and of a cam or eccentric-lever, *x*, pivoted upon the main lever M, and made to operate the auxiliary lever W, all arranged and operated substantially as shown in the drawings.

The ends are connected and held in place by any ordinary stay-bar, M, and rod N.

An ordinary crank-lever, P, is applied, for working the roller.

The swing-lever arrangements F F' may be so made in different machines as to bring the upper roller A directly on the top, or down at the side, at any convenient given point of the under or drive-roller B, by slightly changing the main lever M, or the end supports C and C'.

What I claim as my invention, and desire to secure by Letters Patent, is—

The combination of the rollers A-B, tube *a*, swing-levers F F', main levers M, auxiliary lever W, cam-lever X, and standards S and S', constructed as described, and operating as and for the purposes set forth.

E. P. RUSSELL.
